UNITED STATES PATENT OFFICE.

JOHN A. RAFFERTY AND LAWRENCE M. TAYLOR, OF CAMDEN, NEW JERSEY.

KEY HOLDER.

Application filed July 12, 1924. Serial No. 725,666.

To all whom it may concern:

Be it known that we, JOHN A. RAFFERTY and LAWRENCE M. TAYLOR, citizens of the United States, residing at Camden, in the 5 county of Camden and State of New Jersey, have invented a new and useful Key Holder, of which the following is a specification.

This invention relates to key holders and more particularly to metal non-opening devices of this character.

The object of the invention is to provide a key holder in which a socket is equipped with swivel jointed holders which are removable for attaching and disconnecting a 10 key from the socket.

Another object is to provide a device of this character the holder supporting member of which may be attached to any material desired and in which the individual 20 holders are made removable by pressing them to one side only and exerting a sidewise and outward pull thereon.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed may be made within the scope of what is claimed without departing from the spirit of the invention.

In the accompanying drawings:—

Figure 1 represents a side elevation of a 35 key holder constructed in accordance with this invention shown applied; the keys being shown in dotted lines;

Fig. 2 is a bottom plan view thereof;

Fig. 3 is a longitudinal section taken on 40 the line 3—3 of Fig. 2; and

Fig. 4 is a transverse section taken on the line 4—4 of Fig. 3, the dotted line position of the holder proper illustrating the position assumed during the removal of the 45 holder for the application or removal of a key.

In the embodiment illustrated a socket member 1 is shown preferably of metal which may be of any desired length according to the number of keys to be carried, it being preferably two inches more or less. This socket member is composed of any suitable metal preferably of brass or aluminum being formed from a single sheet folded to 55 be hollow T-shaped in cross section as shown in Fig. 4, the head portion 2 thereof being

provided with a plurality of longitudinally spaced apertures 3 for a purpose presently to be described. The side flanges 4 and 5 of the member 1 are spaced apart a sufficient distance to receive the material M between them and these flanges parallel each other and are equipped at their free edges with inwardly extending spurs 6, those on one side being staggered in relation to those on the other side and which are designed to bite into the material which is used as a support for the holder and be clampingly engaged therewith as is shown clearly in Figs. 1 and 4.

The ends of this socket member 1 are preferably equipped with upstanding flanges 7 struck out as an integral part of the head 2 and which are turned inwardly to close the ends of said hollow head as is shown 70 clearly in Figs. 1 and 3.

Depending from the head 2 of the socket member 1 are a plurality of removable key retainers 8 any desired number of which may be employed according to the number 80 of apertures 3 formed in head 2, five being here shown.

These retainers 8 are made of spring wire bent into substantially elongated U-shaped form and equipped with outwardly extending lateral fingers 9 at their free ends which are designed to be entered through the apertures 3 and engaged with head 2 whereby these retainers have a swiveled connection with said head and are adapted to be disengaged therefrom for the insertion or removal of a key.

When a key K is to be placed on or removed from one of these retainers 8 pressure is exerted on one side or leg of the retainer and a pull sidewise and outward is exerted thereon, the key fastener or retainer being in the position shown in dotted lines in Fig. 4. This operation will release the fastener 8 from the socket 1 and the key K 100 may then be easily slipped on the fastener and the fastener reinserted in the aperture 3 by compressing its legs together sufficiently to permit the fingers 9 to be passed through the aperture into the head and when 105 said fingers are released they will engage the head on its inner face at the opposite sides of the aperture as is shown clearly in Fig. 4.

A key holder constructed as herein shown and described may be cheaply manufactured and may be attached to the lower portion

of a man's vest, to his belt, to a woman's dress or to any other suitable support and the individual keys may be removed and replaced quickly and easily in the manner above described.

We claim:—

1. A key holder comprising a hollow metal socket substantially T-shaped in cross section, the shank portion being double walled and adapted to straddle a support received between said walls, a plurality of apertures in the head of said T-shaped member, and U-shaped spring wire key retainers having means at their free ends for detachably securing them in said socket, said means being entered through said apertures and adapted to swivel therein.
- 15 2. A key holder comprising an elongated

attaching member composed of a single sheet of metal bent to form a socket substantially inverted T-shaped in cross section, the flanges of said members having turned laterally extending prongs along the edges thereof for engagement with a support, the head of said member having spaced apertures, and key retainers each constructed of a U-shaped piece of spring wire having laterally extending outwardly projecting fingers at their free ends adapted to be inserted through said apertures to hold the retainers yieldably engaged with the socket.

In testimony that we claim the foregoing as our own, we have hereto affixed our signatures.

JOHN A. RAFFERTY.

LAWRENCE M. TAYLOR.
